STEAM TRAP

Gustav F. Gerdts, Bremen, Germany

Application December 16, 1935, Serial No. 54,610

6 Claims. (Cl. 137—103)

This invention relates to a steam trap, and it refers more particularly to a device for removing water of condensation from steam conduits, heating installations, steam boiler plants and the like, said device being provided with an enclosed float and being automatically operated by the level of the water acting upon said float.

Automatically operable devices of this type are usually actuated through the application of comparatively little force and their dimensions depend generally upon the dimensions of the float or floating element, the movements of which are transmitted to a very sensitive lever mechanism. Sensitive mechanisms of this type break very easily, particularly as they are subjected to corrosion, water pressure, scale formation and the like. The condensed water frequently flows with a high velocity and may contain a large percentage of oil, dirt and the like. Due to these conditions devices of this type break very often and must be constructed in such manner that the movable parts thereof are easily accessible in order that the operator may inspect them and quickly determine the cause of a breakdown. The necessity of quickly repairing devices of this type is particularly important since a breakdown of one of them may cause considerable loss of steam in the plant.

An object of the present invention is the provision of a device for removing condensate water, the entire movable mechanism of which may be quickly, easily and conveniently inspected.

Another object is the provision of a device having a float which operates a valve closing and opening mechanism, all the parts of the device being readily accessible.

A further object is the provision of a device of this type, all the elements of which may be easily inspected by an operator, particularly as far as the movements and the cooperation of these elements are concerned.

A still further object is the provision of a device for removing a condensate, the operative elements of which may be inspected without removing said device from the conduits to which it is attached.

The above and other objects of the present invention may be realized through the provision of a device comprising a single comparatively elongated central body carrying all the movable parts of the device, and/or all elements which are necessary for the operation of the device, such as the float and the lever connected therewith, valve closing and opening means, passages for transmitting the water to said means, and the like.

This central body thus constitutes the major portion of the casing of the device. According to the present invention, all other parts of the casing have the form of covers or caps enclosing parts which are carried by the central body and which project therefrom, said covers and caps being attached to said central body. In accordance with a preferred form of the invention, the central body carries two caps, one of which covers the float, while the other covers the valve opening and closing mechanism.

The invention will appear more clearly from the following detailed description when taken in connection with accompanying drawings showing, by way of example, preferred embodiments of the inventive idea.

In the drawings:—

Figure 1 is a vertical section through a device constructed in accordance with the principles of the present invention;

Figure 2 is a section along the line 2—2 of Figure 1;

Figure 3 is a side elevation of the valve shown in Figures 1 and 2 with the covers removed.

Figure 4 is a section along the line 4—4 of Figure 1;

Figure 5 shows in side elevation a valve of a somewhat different construction.

Figure 6 is a sectional view of the upper portion of the device illustrating a modification permitting direct connection between the inlet and the outlet passages.

The device illustrated in Figures 1 to 4 of the drawings comprises a central body 6 having the form of an elongated chassis which is comparatively narrow in form. That portion of the body 6 which is situated close to the flange 7 carrying the cover 8 for the float 9, is narrower than the other portions of the body 6.

The body 6 contains an inlet passage 10 through which the water flows through the chamber 11, as indicated by the arrow 12. The valve body 6 also contains an outlet passage 13 which is in communication with a horizontal passage 14 and through which the water flows out of the device 45 in the direction of the arrow 15. A flange 16 is situated substantially opposite the flange 7 and is used for supporting a cover or cap 17 which covers the valve operating mechanism 23.

The body 6 is also provided with a flange 18 which is firmly connected with one end of a pipe 19 through which water is introduced into the inlet passage 10 of the body 6. Another flange 20 is situated at the opposite side of the flange 18 and is firmly connected with an outlet pipe 21.

through which water flows out of the body 6. The interior of the pipe 21 is in communication with the passage 13.

The body 6 comprises also a tubular portion 5 or member 22 which contains the passage 14. The member 22 extends substantially at right angles to the main portion of the body 6 and constitutes an integral part of the body 6. The member 22 carries the valve closing and opening means 23 of the usual type. These means comprise a support 24 carrying a pivot 25 which supports one end of a lever 26, the opposite end of which is attached to the float 9. The bent portion 27 of the lever 26, which is situated adjacent the pivot 25, is provided with two abutments 28 and 29 which are situated on opposite sides of the lever 26. The abutments 28 and 29 are adapted to come in contact with a valve body member 30, which is reciprocably mounted in a guide 31 forming a part of the support 24. Due to this arrangement, an oscillation of the lever 26 causes a movement of the member 30 which opens and closes the outlet opening 32 of the passage 14. The oscillation of the lever 26 is caused automatically by the float 9 which floats upon the water filling the interior 33 of the cover 8.

Bolts 34 are used for attaching the cover 8 to the flange 7 of the central body 6. The cap 17 which covers the valve operating mechanism 23 is situated under a support 35 which is mounted upon a pivot 39 carried by the central body 6. The support 35 is provided with inner screw threads meshing with the screw threads of a bolt 36 having an end portion 37 which may be 35 brought into engagement with a flat surface 38 of the cover 17. Due to this arrangement, the bolt 36 presses the cover 17 against the flange 16 of the body 6. Due to the provision of the pivot 39 the support 35 can be swung to one side when 40 it is desired to remove the cover 17, so that the support 35 does not interfere with the removal of the cover 17.

As shown in Figure 2 of the drawings, the valve body 6 is narrow in form so that the cover 17 is 45 also comparatively narrow. The cover 17 may be made of comparatively thin material such as steel sheets or the like. In the example illustrated, the cover 17 comprises two frames 40 and 41 which carry glass plates 42 and 43.

Due to this arrangement the operator can conveniently observe the function of the valve closing mechanism 23 without removing the cover 17.

The body 6 also carries the adjusting lever 44 having an arm 70 which may be brought in contact with the lever 26 to maintain the valve mechanism 23 in its open position.

The central body 6 also carries a bolt 45 which may be taken out whenever it is necessary to remove the water from the chamber 11.

A small valve 46 is carried by the central body 6 and is in communication with the inlet passage 10. The valve 46 is used to remove the air which flows into the interior of the device along with the water flowing in the direction of the arrow 12.

As shown in Figure 2, the central body 6 is quite narrow in the vicinity of the flange 7, so that the glass plates 42 and 43 may be placed quite close to the mechanism 23 and may be conveniently used for inspecting the operation thereof.

As shown in Figure 3, the cover 8 and the cover 17 may be conveniently removed by unscrewing the bolt 34 and the bolt 36, respectively, which press the two covers tightly against the flange 1 and flange 16 of the body 6. It is apparent that 75 after the covers 8 and 17 have been removed, the

entire mechanism of the device can be easily and conveniently inspected. The highest position of the float 9 is shown by broken lines in Figure 3.

The device illustrated in Figure 5 of the drawings is used in connection with pipe lines which transmit the water vertically from a higher point to a lower point. The device comprises a central body 50 provided with a vertical inlet pipe 51 and a vertical outlet pipe 52. The inlet pipe 51 is provided with a flange 53 and is tightly connected with a vertical pipe 54. The outlet pipe 52 is provided with a flange 55 which is firmly connected with a pipe 56. Water circulates through the device in the direction of arrows 57.

A pipe 58 which is similar to the member 22 shown in Figure 1, forms an integral part of the central body 50 and contains the passage 59, which is in communication with the interior of the pipe 56.

The central body 50 is provided with two flanges 60 and 61 which are situated on opposite sides of the central body. A cap or cover 62 is attached to the flange 60 and is used for the purpose of covering the float. A cap 63 is attached to the flange 61 and is used for the purpose of covering the mechanism which closes and opens the passage 59. This mechanism, as well as the float which operates the same, are similar to those described in connection with the device shown in Figures 1 to 4 of the drawings, and are not illustrated in Figure 5.

It will be apparent that as soon as the two covers 8 and 17, or the two covers 62 and 63 are removed, the float 9 and the mechanism 23 become immediately accessible, so that the operator, 35 by moving the float 9, can easily ascertain how the mechanism 23 operates. Should a breakdown occur, the operator will be able to determine at once the cause and the extent of such a breakdown.

According to the present invention, all the movable elements of the valve are attached to the valve body so that the casings 8 or 62, which surround the float 9 may have the form of thin and light caps.

The valve constructed in accordance with the present invention, has the further advantage that it can resist considerable forces and pressures. The covers 8 and 62 surrounding the float may be made of thin steel sheets, since they do not contain any channels or similar parts, all such channels being formed in the central body 6 or 50.

In the example illustrated in Figures 1 to 4 of the drawings, the two flanges 17 and 16 of the body 6 are situated opposite each other. The flanges 60 and 61 of the valve body 50 shown in Figure 5 are disposed in a similar manner. This arrangement has the advantage that the pipes 19 and 21 and the pipes 54 and 56 may be maintained in alignment with each other.

The further advantage of the device shown in Figures 1 to 4 is that the body 6 with its covers 8 and 17 is situated underneath the pipes 19 and 21, so that these pipes do not interfere with the inspection of and repair work on the device.

The construction of the device in accordance with the present invention has the further advantage that the inlet passage 10 and the outlet passage 13 are situated side by side and substantially parallel to each other.

Due to this arrangement, it is possible to provide a valve or a cock 46a which will establish a direct connection between these two passages as shown in Figure 6, when an examination of the

device's closing and opening mechanism is to take place, so that the device may be inspected without interfering with the steam pressure.

What is claimed is:—

5 1. In a device for removing a condensate, a central body, said central body being of elongated form and having an inlet and an outlet passage formed therein, a mechanism carried by said elongated body and projecting from one side of 10 said body for connecting said inlet passage with said outlet passage and for interrupting this connection, a float projecting from the opposite side of said elongated body, a lever having one end connected with said float and the other end connected with said mechanism, a removable cover carried by said body and enclosing said float, and another removable cover carried by said body and enclosing said mechanism whereby said two removable covers are situated on opposite sides of 15 20 said elongated body, so that the device may be readily inspected.

2. In a device for removing a condensate, a central body having passages for the inlet and outlet of a fluid formed therein, said body comprising two annular flanges situated on opposite sides thereof; two covers, each of said covers being adapted to be attached to a separate flange, and means connecting said inlet passage with said outlet passage, said means comprising 25 30 a valve mechanism carried by said body, a lever operatively connected with said valve mechanism and a float connected with said lever, said float which projects from one side of said central body being surrounded by one of said covers the interior of which is in communication with said inlet passage, said valve mechanism being surrounded by the second one of said covers and projecting from the opposite side of said central body, whereby said device is made readily accessible 35 40 for inspection and repair.

3. In a device for removing a condensate, an elongated body, said body having two substantially parallel passages formed therein, one of said passages serving as an inlet for a fluid while the other one of said passages serves as an outlet for said fluid, two flanges situated substantially opposite each other and forming an integral part of said body, a cover adapted to be connected to one of said flanges, another cover connected to the other one of the said flanges, each of said covers having the form of a hollow container, the interior of the first-mentioned cover being in communication with the inlet passage, a valve mechanism for closing and opening the outlet passage, said mechanism being situated within the second-mentioned cover, and being carried by said body, the interior of the second-mentioned cover being in communication with the interior of the first-mentioned cover, a lever having one end connected with said mechanism and a float situated within the first mentioned cover and connected to the other end of said lever, said float and said valve mechanism projecting from opposite sides of said elongated body.

5 4. In a device for removing a condensate, a

central substantially vertical body having a vertical inlet passage and a vertical outlet passage formed therein and comprising two annular flanges situated substantially opposite each other and in alignment with each other, one of said annular flanges surrounding the end of said inlet passage and being adapted to be connected to an inlet pipe, the other one of said flanges surrounding the end of said outlet passage and being adapted to be connected to an outlet pipe, said central body comprising two other flanges situated below the first-mentioned flanges, a valve mechanism carried by said body for interconnecting said passages and for interrupting this connection, a float, a lever having one end connected with said float and the other end connected with said valve mechanism, a removable cover connected to one of the second-mentioned flanges and enclosing said float, and another removable cover enclosing said valve mechanism and connected to the other one of the second-mentioned flanges.

5. In a device for removing a condensate, an elongated central body having an inlet passage and an outlet passage formed therein and comprising a projecting portion containing a passage which is in communication with said outlet passage, a float, a lever having one end connected with said float, a removable cover carried by said body and enclosing said float, the interior of said cover being in communication with said inlet passage, another removable cover carried by said body and enclosing the projecting portion of said central body, the interior of the second-mentioned cover being in communication with the interior of the first-mentioned cover, a valve mechanism carried by the projecting portion of the central body for interconnecting the passage of the projecting portion with the interior of the second-mentioned cover and for interrupting said connection, said valve mechanism being operatively connected with the other end of said lever, and a pair of glass plates carried by the second-mentioned cover and situated substantially opposite each other and adjacent said valve mechanism.

6. In a device for removing a condensate, an elongated substantially vertical central body having a vertical inlet passage and a vertical outlet passage formed therein and comprising an annular top flange which surrounds the end of said inlet passage and which is adapted to be connected to an inlet pipe, and an annular bottom flange situated substantially underneath said top flange and surrounding the end of said outlet passage; a valve mechanism carried by said body for interconnecting said passages and for interrupting this connection, a float, a lever having one end connected with said float and the other end connected with said valve mechanism, a removable cover carried by said body and enclosing said float, and another removable cover carried by said body and enclosing said valve mechanism.
